ILLUMINATING APPLIANCE

Filed Jan. 2, 1929

INVENTOR,
NICHOLAS C. AMEN.
BY *Martin P. Smith* ATTY.

UNITED STATES PATENT OFFICE

NICHOLAS C. AMEN, OF LOS ANGELES, CALIFORNIA

ILLUMINATING APPLIANCE

Application filed January 2, 1929. Serial No. 329,836.

My invention relates to an illuminating appliance and has for its object the provision of a relatively simple, practical and inexpensive appliance that may be advantageously employed for illuminating purposes or as an illuminated advertising sign.

Further objects of my invention are to generally improve upon and simplify the construction of the existing forms of illuminating appliances and illuminating advertising signs, further to provide a device of the character referred to that is very compact and readily portable in order that it may be conveniently employed for a variety of purposes, and, further to provide an illuminating appliance wherein differently colored rays of light may be projected from the apparatus in order to illuminate in an attractive manner displays of goods or articles in show windows, showcases and the like.

A further object of my invention is to provide an illuminating appliance that includes a plurality of interchangeable windows or sections made up of differently colored transparent panels and to combine therewith a lamp and reflectors so that the differently colored light rays that pass through said differently colored windows or panels will be blended so as to produce highly attractive results when said rays are directed onto goods that are displayed in show windows and the like.

Further objects of my invention are to provide an illuminating appliance that is universally adjustable so that it may be conveniently used for a wide variety of purposes, and, further, to provide means whereby the differently colored transparent sections or advertising panels utilized in the appliance are capable of being readily interchanged, thereby increasing the usefulness of the appliance.

With the foregoing and other objects in view, my invention consists in certain novel features of construction and arrangement of parts that will hereinafter be more fully described and claimed and illustrated in the accompanying drawings, in which:

Fig. 1 is a front elevational view of an il-

luminating appliance constructed in accordance with my invention.

Fig. 2 is a side elevational view of the appliance.

Fig. 3 is a top plane view of the illuminating appliance with portions thereof broken away and in section.

Fig. 4 is a vertical longitudinal section taken on the line 4—4 of Fig. 1.

Fig. 5 is an elevational view of an adjustable clamp that is utilized in the rear portion of the illuminating appliance.

Fig. 6 is a horizontal section taken on the line 6—6 of Fig. 5.

Fig. 7 is an elevational view of a clamping plate that forms a part of my improved illuminating appliance.

Fig. 8 is an elevational view of a modified construction wherein a lens is supported directly in front of that portion of the housing that is provided with the transparent panels.

Fig. 9 is a front elevational view of one of the advertising panels that may be used in my improved appliance.

Fig. 10 is a vertical section taken on the line 10—10 of Fig. 9.

Referring by numerals to the accompanying drawings which illustrate a practical embodiment of my invention, 10 designates a base from which projects upwardly a post or standard 11 and formed integral with or fixed to the upper end of said post is a spherical head 12 upon which the housing of the appliance is adjustably mounted. I prefer to form the base in two parts that are detachably connected by means of screws or bolts 10a and the upper part being considerably smaller than the lower part, thus enabling the parts to be separated and the smaller upper portion secured to a relatively narrow rail or transom within a show case or show window.

The housing 13 of my improved illuminating appliance is preferably formed of sheet metal and is substantially pyramidal in shape with its base either square or rectangular in shape.

Arranged within the housing and spaced a slight distance away from the walls thereof are mirrors or members 14 having reflecting

95

100

surfaces and formed in two or more of the walls of the housing are louvres 15 which permit air to circulate through the chambers between the reflecting members and 5 walls of the housing.

Two of the walls of the housing are provided on their outer faces adjacent to their central portions with threaded apertures 16 that are adapted to receive screws or bolts 10 17, which latter pass through the ends of a bracket 18 and the latter being provided with a centrally arranged flanged aperture that accommodates the upper portion of head 12.

15 By providing two of the walls of the housing with the apertures 16 the plate 18 which serves as a part of the means for supporting the housing on the post 11, may be shifted from one side of the housing to the other 20 with the result that said housing may be conveniently supported flatwise or with the greatest length of its front end horizontally disposed or vertically disposed as may be desired.

25 Positioned on the underside of the plate 18 and secured thereto at one end by screws 19 is a plate 20 provided with a centrally arranged flanged opening 21 for the accommodation of the lower portion of the head 12 and the opposite end of this plate is secured to plate 18 by a bolt 22 on the outer end of which is mounted a winged nut 23.

When plate 20 functions as a clamping plate and when the winged nut 23 on bolt 30 22 is tightened to move plate 20 toward plate 18, the flanges around the openings in the two plates clamp the head 12 on the upper end of post 11, thereby firmly supporting the housing of the appliance in its adjusted position.

40 Formed in the rear end wall of the housing is a flanged opening in which is adjustably positioned a ball 24 and secured on the outer face of the rear wall of the housing 45 is a clamping plate 25 that is practically identical in structure with the clamping plate 20, said clamping plate being provided with a centrally arranged flanged opening that receives the ball 24.

50 The plate 20 is connected to the rear wall of the housing at one end by screws or bolts 26 and at the opposite end by means of a bolt having on its outer end a winged nut 27.

Ball 24 is provided with a centrally arranged aperture 28 for the accommodation of 55 a tube 29, and the body of said ball to one side of this aperture is slotted, as designated by 30 in order that the parts of said ball when subjected to pressure may clamp the rod 29 that passes through aperture 28.

60 The rod 29 projects a short distance into the housing 13 and carried on the inner end thereof is an electric lamp 31. Conductors 32 extend through the tube 29 to the contacts 65 of the lamp and mounted on the outer end of

said tube is a ball 33 that serves as a handle by which the lamp carrying tube is adjusted.

Arranged on the front portion of the top wall of the housing is a hinged panel 34 which, when opened, permits the insertion or removal of windows or transparent sections that form the front wall of the appliances. These windows or panels may be formed of strips or sections 35 of colored transparent material such as glass, or if the appliance is utilized for advertising purposes each window or section may consist of a stencil sheet 36, behind which is positioned a section 37 of opal glass and arranged behind the latter is a section 38 of colored transparent material preferably glass. 70 75 80

The different windows or sections forming the front of the appliance are separated by narrow division strips 39 preferably of metal, and which are substantially H-shape in cross section in order to receive the edges of the sections of material that form the front panels or windows (see Fig. 3).

85 In some instances it may be found desirable to arrange in front of the housing of the appliance a magnifying or concentrating appliance 40, and where such arrangement is carried out the lens is mounted in a suitable frame 41 that is secured to the front portion of the housing.

90 In the use of my improved illuminating appliance the housing containing the lamp and the transparent windows or panels in front, may be universally adjusted upon the head 12 of the standard 11, and by tightening the winged nut 23 on the bolt 22 plates 20 and 18 are clamped upon the head so as to securely hold the housing in its adjusted position.

95 When the winged nut 27 is unscrewed from its bolt to release the clamping pressure of plate 25 and the rear end wall of the housing 100 on the ball 24 the latter may be universally rotated between the flanged edges of the openings in said plate and rear wall and as the clamped pressure on the divided parts of the ball is released the tube 29 may be adjusted 105 lengthwise through the ball, thereby moving the lamp 31 toward or away from the transparent panels or windows at the front of the housing.

110 Obviously the lamp carrying tube 29 may 115 be swung vertically or horizontally upon its axis, which is the ball 24, and thus the lamp may be positioned adjacent to either side or the top or bottom of the housing, as shown by dotted lines in Fig. 4.

120 By tightening the winged nut 27 upon its bolt, plate 25 will be forced toward the rear end wall of the housing and such action will clamp the interposed ball 24, thereby securely holding the same in its adjusted position and at the same time the clamped pressure applied to the ball will clamp and hold the tube 29 in its adjusted position.

125 Direct rays of light from the lamp 32 will 130 pass through the differently colored sections

of glass in the front wall of the housing, thereby producing colored rays to illuminate the goods or objects onto which said rays are directed, which rays correspond, of course, to the color of the respective sections of glass in the front wall of the housing and reflected rays of light will be thrown forwardly by the mirrors or reflecting surfaces within the housing, and these reflected rays in passing through the differently colored panels will produce a combination or blending of the various colors when thrown upon the goods or objects that are illuminated, thus producing very attractive and desirable results.

In tests and experiments with an illuminating appliance having three transparent panels in its front wall and which panels are respectively colored red and blue, I have produced twelve distinct colors which are blends or combinations of the three different colors of the panels, and these twelve color blends are extremely effective in the illumination of various lines of goods displayed for sale or for illuminating any object for the purpose of rendering the same distinctive and attractive.

Obviously by using transparent panels of different or predetermined colors, various striking and attractively shaped color combinations may be produced and directed onto objects to be illuminated.

Where my improved illuminating appliance is utilized as a sign a plurality of removable and interchangeable windows or panels are assembled to form the front wall of the housing, which windows are removed and inserted by opening the hinged member 34, and each panel consists of the front stencil sheet 36, the intermediate section 37 of white or opal glass, and the rear section 38 of colored glass.

Where such an arrangement is utilized the light that passes through the openings in the stencil sheet will be colored as it passes through the rear colored transparent section 38, thereby producing an attractive illuminated sign.

By arranging the section 37 of white or opal glass behind the stencil sheet, the wording or characteristics cut on the stencil sheet will be visible in the daytime or while the lamp within the housing is not lighted, such result being due to the differences in color of the stencil sheet 36 and intermediate section 37.

In some instances, and particularly where flood lighting is desired, the efficiency of the device may be materially increased through the use of a containing lens in front of the housing, as illustrated in Fig. 8.

Thus it will be seen that I have provided an illuminated advertising apparatus that is relatively simple in construction, inexpensive of manufacture, universally adjustable and capable of use for a wide variety of purposes.

It will be understood that minor changes in the size, form and construction of the various parts of my improved illuminating appliance may be made and substituted for those herein shown and described without departing from the spirit of my invention, the scope of which is set forth in the appended claims.

I claim as my invention:

1. In an illuminating appliance, a housing, a plurality of differently colored transparent sections forming one of the walls of the housing, a source of light adjustably mounted within the housing, and a plurality of reflectors arranged within said housing and surrounding the source of light therein, which reflectors are arranged to form a hollow horizontally disposed pyramid, the open large end of which is positioned adjacent to the wall of the housing that is composed of the differently colored transparent sections.

2. In an illuminating appliance, a housing, a plurality of windows forming one of the walls of said housing, each window comprising a stencil sheet, an intermediate section of opal glass, a rear section of colored transparent material, a source of light adjustably mounted within the housing behind said windows and a plurality of reflectors arranged within said housing and surrounding the source of light therein, which reflectors are positioned so as to form a horizontally disposed hollow pyramid at its open base positioned adjacent to the plurality of windows.

3. In an illuminating appliance, a housing, a plurality of windows forming one of the walls of said housing, each window comprising a stencil sheet, an intermediate section of opal glass, a rear section of colored transparent material, a source of light adjustably mounted within the housing behind said windows, and a plurality of reflectors arranged within the housing and surrounding the source of light therein, which reflectors occupy different angular positions with respect to each other and with respect to said windows.

4. In an illuminating appliance, a horizontally disposed pyramid shaped housing, a window arranged in the large end of said housing, a lamp adjustably arranged within the housing and reflectors arranged within the housing around the lamp therein, which reflectors occupy angular planes parallel with the planes occupied by the walls of said housing.

In testimony whereof I affix my signature.
